UNITED STATES PATENT OFFICE.

JAMES MILTON WAUGH, OF CHICAGO, ILLINOIS.

DRAFT-GEAR.

1,143,154.

Specification of Letters Patent. Patented June 15, 1915.

Application filed April 28, 1903. Serial No. 492,302.

To all whom it may concern:

Be it known that I, JAMES MILTON WAUGH, a citizen of the United States, and a resident of the city of Chicago, in the 5 county of Cook and State of Illinois, have invented certain new and useful Improvements in Draft-Gears; and I do hereby declare that the following is a full, clear, and exact description of the same, reference being had to the accompanying drawings, and to the letters of reference marked thereon, which form a part of this specification.

In the evolution of railway rolling stock, nothing has been more noticeable than the 15 constant increase in the weight and load capacity of rolling stock, owing to the constantly increasing traffic, and it has been found that owing to such increase in weight of equipment and load, a draft gear amply 20 sufficient but a few years ago to withstand buffing and pulling stress, is now quite insufficient to withstand the terrific stresses occasioned not only in buffing, but under actual running conditions.

Very numerous attempts have been made 25 to improve and perfect draft gear and rigging to a degree commensurate with the changing conditions, and from the simple spiral spring constructions of a comparatively recent time, powerful friction gears have been installed and an almost infinite 30 variety of spring and friction gears have been put on the market, none of which have, as yet, proven capable of absorbing, for any 35 very extended period of time, the stresses to which they are subjected in buffing and pulling. In consequence, very great expense is occasioned to railway companies for 40 constant repair of draft gears and draft rigging and for the repair of the car under frames because of the spreading of center sills owing to the severe stresses exerted thereon by the friction gears and by the shearing of bolts in various parts of the 45 draft gear owing to the gear proving incapable of absorbing the stresses to which subjected.

The object of this invention is to provide 50 a spring friction draft gear of such capacity as to enable the same to absorb all ordinary buffing and the maximum pulling stresses with but exceedingly slight recoil and comparatively slight inward or outward travel of the gear under such stresses and to afford in connection with such a draft gear

an auxiliary or supplemental gear normally inert in both pulling and buffing, and adapted to come into action only under buffing stresses beyond the normal capacity of the main draft gear.

It is also an object of the invention to afford in connection with a draft gear an auxiliary or supplemental gear inert under pulling stresses and acting appreciably to absorb only such stresses as are beyond the 60 normal capacity of the main gear in buffing.

It is a further object of the invention to afford a draft gear embracing a plurality of groups of resilient friction plates, the 65 plates of each group being in mutual frictional engagement, and adapted to absorb buffing and pulling stresses frictionally, and also because of their resiliency to afford in connection therewith one or more larger auxiliary groups of spring friction plates so 70 disposed as to act only under abnormal buffing stresses.

The invention embraces many novel features and consists in the matters hereinafter described and more fully pointed out and 75 defined in the appended claims.

In the drawings: Figure 1 is a fragmentary top plan view partly in horizontal section of a device embodying my invention. Fig. 2 is a section taken on line 2—2 of Fig. 80 1. Fig. 3 is an enlarged inner face view of the sliding abutment block. Fig. 4 is a view similar to Fig. 1, and illustrating a main draft gear constructed with spiral springs in a familiar manner. Fig. 5 is a central 85 longitudinal vertical section thereof. Fig. 6 is a section taken on line 6—6 of Fig. 4.

As shown in the drawings: A, indicates the parallel center sills arranged as usual, or in any suitable manner as a part of the 90 under frame of the car, and A', the end sill. Rigidly bolted on the center sills and extending below the same, are the check castings B, which extend from near the forward 95 end of the car frame inwardly, if desired, to the body bolster. As shown, said check castings each are constructed to afford a channel b, which fits upwardly around the bottom and sides of one of the center sills A, and integrally connected therewith are 100 downwardly extending webs b', which are of a distance apart and of a width to receive between the same the draft gear as shown in Fig. 6. Each of the webs b' of the check castings is provided at the lower edge with 105 110

an inwardly directed flange b^2 , and an outwardly directed flange b^3 , as shown in Fig. 1, and also is provided between said inner bottom flange b^2 , and the bottom of the channel b , with an inwardly directed, integral stop D, which serves to limit the forward movement of the front follower block C. Supported to slide on the inwardly directed flanges b^2 , of said check castings are abutments or stops D', which are positioned intermediate the stops D, and the rear end of the check castings or irons B. For the purpose of retaining said movable stops D', in place, as shown, each flange b^2 , is longitudinally slotted, as shown in dotted lines in Fig. 1, and as shown in Figs. 3 and 4, a bolt d , extends through the lower portion of said movable abutment D', and through the slot in the flange of said check castings, thus permitting said movable stops to slide longitudinally of the center sills to the extent at least of the length of the slot in said flange. Bearing against said movable stops D' is the rear follower block C', of the main draft gear. A spacing or bearing block e^5 , having an outer convex face, bears against the follower block C', and inserted to slide on the lower flanges b^2 of the check pieces or castings is a group of straight thin, flat, spring friction plates E, composed of any desired number of individual rectangular plates of a dimension to nearly fill the space between the webs b' , and between the under sides of the channels b , and the inwardly directed flanges b^2 , of the check pieces. Bearing against said group of springs E, is a spacing block comprising inwardly tapering wedge shaped members e, as shown, connected by a thin web of metal e' , affording in effect a concave face on each side of said spacing block. Bearing against said spacing block at its ends, is a group of springs E', corresponding in all particulars with the group E, before described, and inserted to bear against the same, is a spacing block e^2 , convex on each side thereof longitudinally, as shown in Fig. 1, and against which a group of plates E², bears at its middle. Bearing against the front face of said group of springs E², is a double concave spacing block e^3 , and inserted between the same and the inwardly directed convex spacing block e^4 , bearing against the forward follower block, is a group of springs E³. As shown, the tail of the draft iron or coupler F, bears against the front follower block C, and riveted or bolted thereto is the draw bar yoke F', which extends around the main draft gear just described, inclosing said follower blocks and groups of plates and spacing blocks therein. The rear end of said yoke lies between the movable follower blocks D'. Desirably, the number of plates in each group may increase from the front toward the rear group, as shown in Fig. 1, in this

manner conveying the inward pressure in buffing gradually from a smaller to a larger group of spring friction plates.

Inserted between the movable follower block D', and any suitable stop at the inner ends of the check castings or pieces, is a forward auxiliary follower block C², concave on its rear face, and a rear auxiliary follower block C³, concave on its forward face, as shown in Fig. 1. Inserted between the same is a plurality of groups of springs indicated by E⁴—E⁵, each group having a greater number of plates than any of the groups of the main draft gear, and separating said groups E⁴—E⁵, is an auxiliary spacing block e⁶, in this instance inasmuch as the engaging face of the follower blocks are concave the spacing block is convex on its sides longitudinally.

The operation is as follows: The number of resilient friction plates in the groups E⁴—E⁵, will, of course, vary with the requirements in individual cases, said auxiliary draft gear being intended to receive and absorb those excessive stresses in buffing that are beyond the normal absorbing capacity of the main draft gear, and for this reason said groups are composed of a sufficient number of plates to render the auxiliary draft gear practically inert under ordinary buffing stresses.

As shown, a carrying plate G, is bolted or riveted beneath the check pieces or castings to support in part the yoke, as shown in Fig. 2, though this is not essential in this type of draft gear for the reason that the yoke may be supported wholly upon the follower blocks and friction springs, if desired. Of course, if desired, such an auxiliary buffing gear may be employed in connection with other types of main draft gears than that shown in Figs. 1 and 2, and as shown in Figs. 4 and 5, a draft gear indicated as a whole by H, and constructed of a plurality of spiral springs arranged tandem, is engaged within the yoke F'. The rear follower block C² however, in that instance bears against the movable abutment D', as before described, and the buffing stress is thereby delivered to the auxiliary buffing gear as the main draft gear H, nears the limit of its absorbing capacity. It is therefore obvious that the auxiliary buffing gear such as described may be employed in connection with any type of draft gear, whether spring or friction, in each instance serving to absorb such abnormal stresses in buffing as would otherwise be likely to result in serious injury or destruction of the main draft gear.

Owing to the construction and width of the movable abutment blocks D', which are sufficiently wide to exceed the maximum inward travel of the yoke F' under full compression of all the groups of springs in the

main draft gear, it follows that the yoke can never contact with the front auxiliary follower block C², but that instead the direct pressure from the rear follower block 5 C', and the groups of springs when approaching their maximum compression is transmitted through the movable abutment block D', to the auxiliary buffering gear, in this manner affording for the main draft 10 gear an additional absorbing capacity for buffering stresses not heretofore attainable.

Of course, in pulling, the main draft gear only is under compression, the auxiliary buffering gear being wholly inert and the movable abutment blocks D' being forced thereby forwardly to the extreme limit of their forward travel. Thus, if desired, the main draft gear may be constructed with relatively low absorbing capacity for pulling 20 stresses, but taken in conjunction with the auxiliary buffering gear, any desired absorbing power may be obtained in buffering. Furthermore, by the use of the auxiliary buffering gear such as described, draw bar travel 25 under compression may be increased to any desired extent in conformity with recent requirements on certain roads.

By the use of comparatively thin, flat, straight, rectangular plates in groups in full 30 bearing face to face in each group, I utilize the adhesive friction due to the enormous bearing surfaces exposed to pressure, which is approximately in each group, twice the area of a single plate multiplied by the number of plates in each group, and which, much more than the resiliency of the plates, tends to resist the flexing of the plates under pressure and acts to almost wholly absorb the recoil, rendering this type of construction 40 particularly valuable as obviating destructive recoil after buffering stresses, which sometimes results in the destruction of certain other types of draft and buffering gears.

Of course, numerous details of the construction may be varied, and numerous other variations and details of construction and application will suggest themselves such as varying the number of groups and the arrangement of groups of springs. I therefore do not purpose limiting myself otherwise than necessitated by the prior art, but do purpose claiming broadly the employment of an auxiliary and buffering gear of high absorbing capacity in connection with 55 a main draft and buffering gear of any type.

I claim as my invention:

1. The combination with a main draft and buffering gear, front and rear stops therefor, said front stop being connected to the 60 side sills, of an auxiliary buffering gear located to the rear of said main gear and comprising flat spring friction plates arranged face to face in groups, and spacing members bearing alternately at the ends 65 and at the middle of said groups, said rear

stops constituting sliding spacing means between said main and auxiliary gears adapted to transmit excessive buffering strains from said main gear to said auxiliary gear.

2. The combination with a main draft and buffering gear including the followers, of a coacting auxiliary buffering gear in alignment therewith and embracing spring friction plates arranged face to face in a plurality of groups, bearings therefor alternate at the middle and at the ends of the groups, and sliding spacing means interposed between the two gears acting to communicate excessive stress from the rear follower of the main gear to the auxiliary gear.

3. In a device of the class described the draft arms, the main draft and buffering gear therein and the followers therefor, an auxiliary buffering gear in said draft arms at the rear of and in alignment with the main gear, and comprising duplicate flat spring friction plates arranged face to face in groups, spacing members bearing alternately at the ends and at the middles of the groups, and slideable followers interposed between the main and auxiliary gear acting to communicate excessive stresses from the rear follower of the main gear to the auxiliary gear.

4. The combination with a main draft and buffering gear, the yoke and followers therefor, of an independent auxiliary spring friction gear positioned to compress in a direct line with the main draft gear, and slideable followers, one on each side of the yoke and bearing against the rear follower of the main draft and buffering gear and the front of the auxiliary buffering gear.

5. The combination with a main draft gear, of movable abutment blocks slidably supported on the under frame and against which the rear follower block of the main draft gear bears, and an auxiliary resilient and frictional buffering gear inserted at the rear of the movable abutment blocks comprising transversely extending spring plates arranged in groups and against one group of which said movable abutment blocks bear to deliver thereto buffering stresses beyond the normal capacity of the main draft gear.

6. An auxiliary buffering gear inserted at the rear of a main draft and buffering gear and the followers therefor and embracing a plurality of groups of relatively thin, flat, spring friction plates in frictional bearing in each group for their entire face surfaces, spacing blocks arranged between said groups to separate the groups alternately at their ends and at their centers, and horizontally moving abutment blocks between the auxiliary buffering gear and the rear follower of the main buffering gear.

7. The combination with a main draft and buffering gear and the followers therefor affording sufficient capacity for ordinary pulling and buffering stresses, of an auxiliary

spring friction buffing gear and its followers arranged at the rear thereof, and longitudinally slid able followers engaged between the rear follower of the main draft 5 and buffing gear and said auxiliary gear, inert on pulling stresses and acting with the main gear to deliver excessive buffing stresses to the auxiliary buffing gear when said main gear is substantially at the limit 10 of its capacity.

8. The combination of a main draft and buffing gear, a yoke and followers therefor, an independent auxiliary friction gear

positioned to compress in a direct line therewith, and slid able spacing means, interposed between the two gears, said means engaging the front follower of the auxiliary gear and the rear follower of the main gear on opposite sides of the said yoke. 15

In testimony whereof I have hereunto 20 subscribed my name in the presence of two subscribing witnesses.
